UNITED STATES PATENT OFFICE

2,095,199

APPARATUS FOR ORNAMENTING PAPER
OR THE LIKEJames Speed, Longmeadow, Mass., assignor to
Strathmore Paper Company, West Springfield,
Mass., a corporation of Massachusetts

Application April 16, 1936, Serial No. 74,711

6 Claims. (Cl. 101—32)

This invention relates to improvements in apparatus for ornamenting material in sheet and web form, such as paper or the like.

The principal objects of this invention are directed to the provision of novel apparatus for ornamenting or finishing paper or the like in web or sheet form. This is accomplished by the provision of a more or less yieldable body having a surface formed to provide a pattern with which it is desired to ornament or finish the sheet or web. In paper manufacture it is desired to provide paper with ornamentation or finishes of various characteristics and as an example it might be desired to ornament paper to simulate 15 a certain type or kind of fabric. According to this invention fabric is associated with the aforesaid body which is more or less resilient in such a way that the fabric becomes the surface of the body and is adapted for use as a printing member 20 or as a member for indenting the paper. In this way coloring may be applied to the said member which applies it to the paper and thereby the paper is imprinted according to the surface so that the ornamentation will simulate the pattern of the fabric employed for the surface or imprinting member. Where the coloring is not used, the paper is finished or indented by the fabric.

In one way a body is made from some plastic 30 such as rubber or a rubber composition which is superposed on a relatively rigid member such as a plate or roll, and the imprinting surface member in the form of a fabric or the like is vulcanized to the face of the body. Then the 35 paper or the like in web or sheet form is contacted with the imprinted member and is ornamented or finished according to the imprinting member.

According to the prior art it has been usual 40 practice in one way to ornament paper by means of engraved or specially prepared plates or rolls but these are extremely expensive and for each different pattern it is necessary to have a separate roll or plate. According to this invention 45 the body is carried by a rigid member such as a plate or roll and may be removed therefrom so that a roll may have a multiplicity of design- applying surfaces applied thereto at small expense.

As an added feature, I have found that where 50 fabric is used for what may be called the printing or finishing face, there may be many varied and beautiful effects, and the elements of the 55 fabric, being of fibrous materials, readily absorb

coloring material when it is desired to apply a colored design to the paper.

Various other novel features and advantages 5 of the invention will be hereinafter more fully referred to in connection with the accompanying description of the preferred form of the invention, reference being had to the accompanying drawing wherein:

Fig. 1 is a diagrammatic sectional elevational view of one form of apparatus to explain the 10 novel features of the invention;

Fig. 2 is a side elevational view of a roll embodying one form of the invention;

Fig. 3 is a fragmentary plan view of an imprinting or finishing member of the invention; 15

Fig. 4 is a cross-sectional elevational view on the line 4—4 of Fig. 3.

Referring now to the drawing more in detail, 20 the invention will be fully described.

According to the invention I provide a body 2 which is preferably formed of some plastic material, such as rubber or a rubber composition. This may be vulcanized to any desired degree and retain some of its yieldability or resiliency. 25

This body 2 has on its face an imprinting or finishing member indicated generally by 4 and which may take various forms. That is, the imprinting member 4 may be a fabric woven from various materials, or, of course, it may be a 30 knitted fabric. Various members will produce many and various effects according to their characteristics, the form of fabric shown being merely for illustrative purposes.

The imprinting member 4 has a part of its 35 elements 6 imbedded more or less in the body 2 and it is vulcanized to the body 2 so that the imprinting member and the body form a composite member. It will be appreciated that the elements of such a member as 4 may be em- 40 bedded more or less in the body as may be desired so that more or less of the fabric will appear at or more or less above the surface of body 2.

The body 2 may be secured to a plate such as 45 9 or to a roll represented by 8 so as to form a more or less resilient covering having the imprinting fabric as the face thereof with the body 2 backed up by a rigid support. The vulcanizing of the imprinting fabric 4 to the body may be accomplished in the usual well-known manner. It will be appreciated that the covering with its imprinting face may be removed from its support very readily so that other bodies and imprinting surfaces may be placed thereon thus 50 55

making it possible to have a wide variety of patterns.

Thus, it is possible to ornament paper with various patterns without the necessity of expensive engraved or etched rolls or plates for the ornamenting operation. The body 2 may be secured to its support either the plate or roll by cement or the like.

With the body having the imprinting fabric face on a support such as a plate or roll, the paper is contacted with said fabric under pressure so that the paper receives an impression according to the characteristics of the fabric.

Where it is desired to apply color to the paper, the fabric face or the elements of the fabric are supplied with color and the paper contacted therewith. For instance, where the imprinting member is used in association with the roll I have found that the roll such as 8 may be placed in a roll-stack consisting of an upper roll 10, a color roll 12 and an intermediate roll 14. The color roll 12 operates so that its periphery at least picks up color in a vat 16 and this roll 12 delivers the color to the roll 14 which is in contact with the ornamenting roll 8 so that the color is applied to the elements constituting the imprinting surface of the said roll 8.

Sheets or webs may be run between the rolls 8 and 10. For instance, a web W of paper which is run from a roll 20 through the rolls 8 and 10 is reeled up as in roll 22. As the paper in web or sheet form is contacted with the imprinting member it is ornamented according to the character of said member which of course may be varied within wide limits.

As I have said heretofore, the fabric member for imprinting the paper may be embedded in the body 2 to any desired extent so that it is possible to obtain ornamentation which is rather bold or which may be relatively faint. In the case of a fabric made from relatively heavy yarn or elements, a faint effect may be produced by embedding the fabric deeply in the body 2. Where a fabric made from relatively small or fine elements is used, these may be laid on the face of the body without any great degree of embedding.

It will be appreciated that it is possible to produce many and various effects since the imprinting member may take many and various forms and that altogether there is produced in an economical manner an efficient imprinting member.

While I have described the invention in great detail and with respect to a preferred form thereof, it is not desired to be limited thereto since many changes and modifications may be made therein without departing from the spirit and scope of the invention.

What it is desired to claim and secure by Letters Patent of the United States is:

1. In apparatus for ornamenting or finishing paper or the like comprising, a relatively rigid support and a relatively yieldable body on said support having an imprinting fabric member vulcanized to the surface thereof so as to have portions thereof embedded therein and other portions extend above the plane of said yieldable body.

2. An apparatus for ornamenting or finishing paper or the like, a relatively rigid roll, a body therearound of relatively yieldable material secured thereto, an imprinting member of fabric secured to the surface of said body so as to have portions of the elements of the fabric embedded therein and other portions disposed above the plane of the surface of said yieldable body.

3. An apparatus for ornamenting or finishing paper or the like, a relatively rigid roll, a body of relatively yieldable material secured therearound, an imprinting member of fabric on the face of said body having some of its elements secured thereto whereby the said body serves as a cushion between said roll and imprinting member, and another relatively rigid roll in coacting relation with the first roll so that a web of paper may pass therebetween to be acted upon by said imprinting member.

4. As a new article of manufacture, a unitary device for working on paper or the like comprising in combination, a body of relatively yieldable vulcanizable material, and a surface on said body formed from a plurality of elements secured to the body by vulcanization so that certain portions of certain elements extend above the plane of the body.

5. As a new article of manufacture, a unitary device for working on paper or the like comprising in combination, a body of relatively yieldable vulcanizable material, and a surface on said body formed from a plurality of elements secured to the body by vulcanization so that certain portions of certain elements extend above the plane of the body, the said material of the body being a rubber-like composition.

6. As a new article of manufacture, a unitary device for working on paper or the like comprising in combination, a relatively rigid roll member, a removable body member of relatively yieldable vulcanizable material extending around the periphery of said roll, and a design-imparting member formed from a plurality of spaced-apart fabric elements secured to the outside of said body member by vulcanization so that portions of some at least of said elements embedded in the vulcanizable material and other portions of some at least of said elements extending above the plane of the body member.

JAMES SPEED.
